UNITED STATES PATENT OFFICE.

EHREGOTT THEODORE WINKLER, OF PHILADELPHIA, PENNSYLVANIA,
ASSIGNOR, BY MESNE ASSIGNMENTS, TO THE AMERICAN ICE MACHINE
COMPANY.

CONDENSER-COIL FOR ICE-MAKING MACHINES.

SPECIFICATION forming part of Letters Patent No. 452,535, dated May 19, 1891.

Application filed September 20, 1887. Serial No. 250,219. (No model.)

To all whom it may concern:

Be it known that I, EHREGOTT THEODORE WINKLER, a subject of the Emperor of Germany, having declared my intention to become a citizen of the United States, residing at Philadelphia, in the county of Philadelphia and State of Pennsylvania, have invented certain new and useful Improvements in Condenser-Coils for Ice-Making Machines, of which the following is a specification.

My invention has relation to that class of ice-making or refrigerant apparatus which is provided with coils connected in the system in such manner as to freely allow them to expand or contract as the variation of temperature in the machine may require. In this class of apparatus the use of couplings—L's, T's, nipples, and unions—is avoided as far as can be, as the expansion and contraction will cause them to leak. To dispense with as many of these joints as possible, it is customary to use whenever possible a pipe of sufficient length and bent in the desired form to connect the two points. In bending pipes, as well known, a great difficulty is experienced in getting the end of the pipe to register with the coupling or other opening that it is to enter, so that the screw-threads of the pipe will not cross the screw-threads of the coupling or other opening, as such opening not only destroys the thread, but makes an unsafe as well as a leaky joint. This is particularly the case with valves, as they have two or more openings which must be connected with pipes often placed at different angles, and one of which is subject to expansion and the other to contraction, as is the case with the valve at the outlet end of a condenser or the inlet end of an evaporator. To avoid this objection, the pipe to be connected to the valve is screwed into a gland having its bore screw-threaded to correspond with the screw-thread in the pipe and its outside smooth or without screw-threads and entering a non-screw-threaded opening or box in said valve, which entrance is easily accomplished, as no centering to prevent screw-threads from crossing is necessary.

Another defect of this class of apparatus is the gumming or clogging of the valves, due to the collection of dirt, oil, and iron sealings

from the metallic pipes getting in the space between the plug-seats and plug when the latter has been set for admitting a proper supply to the inlet-pipe. This accumulation of material ultimately fills the reduced opening through which the fluid escapes from the valve into the expansion pipe or coil and finally clogs the pipes back of it. To clean the valves and pipes, it has heretofore been necessary to remove the valve and pipe from their other attachments, then blow or otherwise clean them, and then replace them in the circuit. This is remedied in my device by forming on the end of the plug a plunger of less diameter and of greater length than the reduced opening in the valve, so that when the plug is seated the end of the plunger projects beyond the lower end of the reduced opening and will have punched a hole through any clog that may have formed in the reduced opening. Furthermore, the plug can be raised above the horizontal opening, so that the full force of the fluid can be driven through the valve not only to clean the latter, but to clean the coils as well.

My invention accordingly consists of constructions and combinations, all as will hereinafter be set forth in the specification and pointed out in the claim.

Reference being had to the accompanying drawings, Figure 1 represents a transverse section, partly in elevation, of a condenser, showing a coil and its cut-off valve embodying my invention; and Fig. 2 is a side elevation of same, drawn to a small scale.

A represents the condenser, comprising the usual water-tank B and a system of coils of pipe C in said tank, and D is the common supply-pipe for the coils C. Each coil C is a separate coil, and is either composed of a single-piece of tubing or of sections welded together, so as to be without screw or other like joints. One end c of each coil is connected to pipe D, as shown, in the usual manner, and the other end c' passes out of the tank B through a stuffing-box b and screws into the smooth or unthreaded gland e for a correspondingly-formed stuffing-box e' on the cut-off-valve casing e². This gland e is loosely mounted upon bolts e³, having nuts e⁴ on 100

their outer ends to retain the gland in position and to admit of regulating or adjusting the density of the packing in the stuffing-box. As the gland e is loosely supported upon bolts e^3 and the end c' of the coil is screwed into the gland, it and the end c' are capable of a simultaneous lengthwise movement to compensate for the expansion and contraction of the coil. This movement, however, is slight, for the reason that as the coil is practically in a single piece or without screw-coupling joints its component parts or winds are free to expand independently. Hence the resultant expansion and contraction are small, and this, as before stated, is compensated for by the movement of the end c' of the coil and gland e . By screwing the coil end c' to the gland e of the stuffing-box e' the valve E is firmly supported upon the pipe end c' , either in a vertical, angular, or other position, without necessitating additional support, which is a desirable feature in setting up the condenser-coils and making pipe connections with their cut-off valves E .

The ease with which the smooth-surfaced gland can be inserted in the valve-opening is a great advantage over the old form, wherein the screw-threaded end of a pipe had to be centered to properly engage with the screw-threaded opening of a valve.

The valve E is preferably composed of an elongated tubular casing e^2 , having a screw-stem e^{20} for the plug e^4 , a stuffing-box e^5 at the top for said stem, a seat e^6 for plug e^4 , and a bottom stuffing-box e^7 , having a gland e^8 , loosely supported upon bolts e^{31} , in a manner as above described for gland e .

In gland e^8 is screwed the pipe f , leading to the expansion-coils. (Not shown in the drawings.) When the pipe f is the end of an expansion-coil or leads thereto, it is of a larger diameter than that of coil end c' , and the stuffing-box e^7 for pipe f is correspondingly larger than the stuffing-box e' for coil end c' . As both of these boxes have the sliding glands, the expansion and contraction of the condenser-coils and of the pipes f , whether they are the ends of the expansion-coils or otherwise, are compensated for in the cut-off-valve stuffing-boxes, and the construction of these boxes or their glands admit of readily erecting or setting up the coils and of disconnecting them whenever it is desirable to do so. The plug e^4 is conical in form and terminates in a stem or plunger g , which is of a smaller diameter than that of the bore of a correspondingly-shaped opening e^9 , leading from the conically-shaped seat e^6 for plug e^4 . The plunger g is also longer than the passage e^9 , so that when the plug is seated the end of the plunger extends beyond the passage. The plug e^4 can also be raised without removing the stem-packing and gland to a point above the inlet-opening e^{10} of the valve, which

will then have free communication by way 65 of plug. The inlet-opening e^{10} of valve E communicates by way of plug-seat opening with the contracted opening e^9 , which is the outlet of the valve. The plunger or needle g , sliding or moving in the outlet-opening e^9 as the valve is opened and closed, 70 cleans it of any dirt or débris tending to collect therein and keeps it always open, so that the valve cannot clog up. By opening valve E to its full extent the pressure in the condenser-coil drives any dirt therein through the valve into the larger or expansion pipe, and after such cleansing the plunger g , when 75 the valve E is closed, pushes out any dirt lodging in the outlet e^9 , so that when next 80 opened the way through the valve is open or clean. This cleansing is, it will be noted, effected without removing the valve from the pipes c' or f and without disconnecting one coil from another. Hence any one coil may at any 85 time be blown or cleaned out by the pressure in the condenser without disturbing the flow through the other coils. The screw part of the stem e^{20} of the valve E is made larger in 90 diameter than that of the stem itself, and the opening in the valve-casing therefore is of a corresponding size and has a shoulder e^{11} near the top of the casing, upon which rests a loose washer or plate h , through which the stem e^{20} passes. This washer forms the bottom or end 95 of the stuffing-box e^5 , the gland e^{12} therefore being smooth or unthreaded, and is provided with or inclosed by a screw-cap e^{13} , which screws to the outside of the casing e^2 . By uncoupling the cap e^{13} and raising the stem e^{20} 100 the upper end of the screw part of the stem abuts against washer h to remove or raise it, the packing above it, and the gland e^{12} out of the casing for replacement of any of said parts for access to its valve or for other purposes.

The stuffing-boxes b for the coils c' prevent escape of water or liquid from tank B . I do not herein limit myself to the details of construction of the parts above described except when specifically claimed, as it is evident that the same may be varied without departing from the spirit of my invention.

What I claim is—

In the circuit of an ice-making or refrigerating apparatus, a valve having the outlet and inlet openings at angles to each other and the latter provided with a plug-seat, and said plug having a plunger of greater length than that part of the opening below the plug-seat.

In testimony whereof I affix my signature in presence of two witnesses.

E. THEODORE WINKLER.
